Primary Examiner — Darlington Ly(74) *Attorney, Agent, or Firm* — Banner & Witcoff, Ltd.(57) **CLAIM**

The ornamental design for a portable nailing machine body, as shown and described.

DESCRIPTION

FIG. 1 is a top, front, and left side perspective view of a portable nailing machine body showing our new design;

FIG. 2 is a top, rear, and right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings illustrate portions of the portable nailing machine body that form no part of the claimed design.
